Primary Examiner — Daniel J Domino

(57) **CLAIM**

The ornamental design for a display screen with graphical user interface, as shown and described.

DESCRIPTION

1. Display screen with graphical user interface

1.1: Front

1.2: Back

1.3: Top

1.4: Bottom

1.5: Left

1.6: Right

The broken lines showing an electronic device illustrate environmental subject matter, whereas the remaining broken lines illustrate portions of the article. None of the broken lines form part of the claimed design.

1 Claim, 6 Drawing Sheets
